UNITED STATES PATENT OFFICE.

EDWARD C. DAMROW, OF FOND DU LAC, WISCONSIN, ASSIGNEE TO DAMROW BROTHERS COMPANY, OF FOND DU LAC, WISCONSIN, A CORPORATION OF WISCONSIN.

MEASURING APPARATUS FOR WHEY AND THE LIKE.

Application filed January 27, 1926. Serial No. 84,089.

This invention relates to that type of automatic fluid measuring and dispensing apparatus, such as used in cheese factories and creameries to prevent an over delivery of 5 whey or skim milk in the delivery of an allotted amount of the same to a dairyman, and the present improvement has for its objects:—

To provide a structural formation and 10 combination of parts and mechanisms, wherein a rotary fluid motor arranged in the outflow duct or passage of a storage tank is operatively connected to a controlling mechanism, capable of adjustment from a 15 remote point such as the office of the works, to permit an outflow or delivery of the proper allowance of the tank contents to a particular dairyman, before effecting an automatic stoppage of the delivery.

20 To provide in an apparatus of the type described, an automatic control mechanism whereby the manual opening means of the outlet valve of the storage tank is rendered inoperative when the controlling mechanism is at its normal starting or zero point, and is restored to an operative condition with the setting of such controlling mechanism for a predetermined delivery of fluid, all as will hereinafter more fully appear.

30 In the accompanying drawings:—

Fig. 1, is a front elevation of the interconnected setting and controlling mechanisms of the present invention, with the storage tank and its outlet duct shown in 35 section.

Fig. 2, is a side elevation of the controlling mechanism, in its associated relation with the outlet valve stem of the storage tank.

40 Fig. 3, is a detail horizontal section on line 3—3, Fig. 4, of the disengaging connection between the controlling mechanism and the outlet valve stem.

Fig. 4, is a detail vertical sectional elevation of the same, on line 4—4, Fig. 3.

Fig. 5, is a detail elevation, partly in axial section, of the main gear wheel and the frictionally associated disk of the controlling mechanism by which the disengaging connection aforesaid is controlled.

Fig. 6, is an axial section of the setting connection which is remotely located from the controlling mechanism.

Like reference numerals indicate like parts 55 in the several views.

In the illustration of the invention, an ordinary whey or skim-milk containing tank 1 is shown, provided at bottom with a delivery duct or pipe 2, the inlet mouth 3 of which duct is controlled by a downwardly seating movable valve head 4 capable of manual operation, when the same is permitted by the present automatic controlling mechanism. In the construction shown the valve stem 5 of the valve head 4 extends to the top of the tank 1 and has guiding engagement in the supporting frame of the controlling mechanism of the invention. The valve stem 5 is tubular in form so as to receive the driven shaft of the rotary fluid motor now to be described.

Within the delivery duct 2, and immediately beneath the valve head 4, a rotary fluid motor 6 is arranged. Said motor is preferably of the turbine type, the stator of which is fixed in the wall of the duct 2 while the rotor 7 is carried by a shaft 8 extending up through a central orifice in the valve head 4 and up through the tubular valve stem 5 for operative engagement with the driving gearing of the automatic controlling mechanism of the invention.

The automatic controlling mechanism above referred to comprises a stationary frame 9 having fixed attachment above the tank 1 and having guides for the valve stem 5 and motor shaft 8 aforesaid.

Near its upper end the frame 9 is formed with a journal bearing for a transverse shaft 10, one end of which carries a worm wheel 11, for operative engagement with a worm wheel 12 fixed in the upper end of the motor shaft 8 aforesaid. The other end of the shaft 10 carries a pinion 13 for operative engagement with the main gear wheel 14 of the present controlling mechanism, the construction providing a slow rotation of the gear wheel 14 and parts carried thereby in a contra-clockwise direction.

The gear wheel 14 is revolvably mounted on a stub shaft 15 projecting laterally from the supporting frame 9, and in direct frictional contact with one face of said gear wheel 14, a circular disk 16 is also revolvably mounted on the stub shaft 15, so as to normally turn with the gear wheel 14, under such frictional engagement between the parts. Such contact however permits of a turning adjustment of the disk 16 in a clockwise direction independent of the gear wheel.

14 for the setting purpose hereinafter more fully set forth. The degree of frictional engagement between the gear wheel 14, and disk 16, may be varied by any usual means, usually an adjusting nut 17 on a screw threaded portion of the stub shaft 15, and an intermediate compression spring 18 and bearing washers 19 as shown more particularly in Fig. 5.

10 Upon the outer face of the aforesaid disk 16, an operating stud or tappet 20 is arranged for the purpose hereinafter set forth, while said disk is formed with a peripheral groove in which a cable 21 is arranged and 15 secured to afford means for effecting a turning adjustment of the disk 16 independent of its frictional engagement with the gear wheel 14.

The cable 21 passes to and around a 20 sheave 22 mounted on the upper part of the supporting frame 9, and from thence over and around other guide sheaves to the hereinafter described setting mechanism of the present improvement.

25 In bearings on the supporting frame 9 and adjacent to the tubular valve stem 8, a shaft 23 has vertical movement, with its upper end connected to a pull connection, preferably a cable 24 which extends over 30 and between suitable guide sheaves 25 to an operating handle 26 located within convenient reach of and for operation by a dairyman or other person that is to receive an allotted amount of the fluid contents of 35 the storage tank 1. Midway its vertical height the shaft 23 is provided with a lateral bearing plate or flange 27 adapted for operative contact with the operating stud 20 of the controller disk 16 aforesaid. The 40 bearing plate 27 is of greater height than the normal vertical movement of the shaft 23 in order that in the vertical movement of the shaft and its bearing plate 27, said bearing plate will continue in operative contact with the aforesaid operating stud 20.

45 Active operative contact of the stud 20 with the bearing plate 27 to hold the same in the retracted position, shown in full lines in Fig. 3, against the pulling stress of a spring 50 28, will prevail during the period in which the controlling mechanism is at its starting or zero point of indication, with the stud 20 in holding engagement against the bearing plate 27.

55 Adjacent to the bearing plate 27, and usually forming a part thereof, an oppositely extending toe 29 is fixedly attached to the shaft 23, and adapted in one position of the timing mechanism parts, to engage 60 beneath a circular collar 30 on the valve stem 5 aforesaid to effect an operative connection between the vertical shaft 23 and the valve stem 5, so that the outlet valve 4 may be raised to an open condition by a 65 manipulation of the handle 26 and cable 24,

on the part of the person who is to receive the allotted quantity of fluid from the storage tank 1 in order that such person must maintain the valve raising mechanism in the described position during the delivery of the allotted amount of liquid. The described operative engagement between the shaft 23 and valve stem 5, automatically takes place when the controlling mechanism is set for an allotted delivery of fluid from the storage tank, in which case the operating stud 20, has been moved out of the described holding engagement with the bearing plate 27, so that the spring 28 is free to turn the parts 75 so that the toe 29 will be in lifting engagement with the collar 30 on the stem of the outlet valve 4.

With gradual return of the controlling dial 16, to the zero point of indication, the operating stud 20 returns to an operative 85 engagement with the bearing plate 27, to turn the same and break the operative connection between the shaft 23 and the stem of the outlet valve 4, so that no further manual operation of said valve and delivery of fluid can be effected until after a 90 fresh setting of the controlling mechanism is made.

The setting means or mechanism, preferably comprises a revoluble adjusting means 95 attached to the operating cable 21 of the controlling mechanism heretofore described, and having a detail construction as follows:

An enclosing casing 31, adapted for fixed attachment to the office wall of a cheese factory or the like, is provided on an outer face with a circular scale or marking 32 and centrally thereof with bearings for a revoluble carrying shaft 33, of the setting mechanism. 100

At one end of the shaft 33, and at the exterior of the casing 31 a hand or pointer 34 is secured in indicating relation to the scale or markings 32 aforesaid, to afford an accurate indication of the extent of adjustment made and required. 105

Within the casing 31, a disk or wheel 35 is fixedly secured to the shaft 33 as shown in Fig. 6, so as to turn in unison with the hand or pointer 34 as the same is adjusted by a person in charge to the desired or allotted measurement. The disk or wheel 35 is a counterpart in size and formation of the controlling disk 16 aforesaid, and has operative engagement therewith by the cable 22 aforesaid, by attachment to the terminal or end of the cable opposite to the cable end that has the before described attachment to the controlling disk or wheel 16, as illustrated in Figs. 1 and 6, and with such cable terminal or end fitting and secured in a peripheral groove in the disk 35, as illustrated in Fig. 6. The arrangement and connection of parts is such that a turning movement of the hand or pointer 34 and associated wheel 35 to the right, or in a 110

clockwise direction, will impart corresponding turning movement of the controlling disk 16 in a like direction, so that when the hand or pointer 34 is set by hand to a pre-determined allotment of fluid to be released, the operating stud 20 of the controlling disk 16 will be moved a corresponding distance away from the trip plate 27, to enable the outflow of the allotted amount of fluid, before said stud by a contra-clockwise movement operates the trip plate to release the outlet valve 4, and prevent further manual opening of the valve. In the gradual return movement of the operating stud 20, towards the trip plate 27, a complementary return of the setting mechanism to its starting or zero point is effected by the connecting cable 22.

Having thus fully described my invention, what I claim and desire to secure by Letters Patent, is:—

1. In an automatic fluid measuring apparatus of the type described, the combination of a storage tank and its outlet duct, a valve controlling said outlet duct, manual means for opening said valve, a rotary fluid motor arranged in said duct, a controlling means operatively connected to said motor, a separable connection forming a part of said manual means and adapted for alternate operative engagement with and disengagement from the aforesaid outlet duct valve, and an adjustable operative means carried by the controlling mechanism for controlling the movement of said separable connection.

2. In an automatic fluid measuring apparatus of the type described, the combination of a storage tank and its outlet duct, a valve

controlling said duct and having a vertically arranged tubular stem, a rotary fluid motor arranged in said duct beneath said valve and having a motor shaft extending up through said tubular valve stem, a controlling mechanism operatively connected to the upper end of said motor shaft, a disk adjustably attached to said controlling mechanism and having an eccentrically arranged operating stud, manual means for opening said valve, and a separable connection between said manual means and said valve stem arranged in the path of the stud aforesaid for operation thereby.

3. In an automatic fluid measuring apparatus of the type described, the combination of a storage tank and its outlet duct, a valve controlling said duct and having a vertically arranged tubular stem, a collar fixed on said valve stem, a rotary fluid motor arranged in said duct beneath said valve and having a motor shaft extending up through said tubular valve stem, a controlling mechanism operatively connected to the upper end of said motor shaft, a disk adjustably attached to said controlling mechanism and having an eccentrically arranged operating stud, manual means for opening said valve, and a separable connection between said manual means and said valve stem, and comprising a vertically movable shaft attached to said manual means and provided with a lateral operating flange arranged in the path of the aforesaid operating stud and an oppositely extending toe adapted for operative engagement beneath a collar of the valve stem.

Signed at Fond du Lac, Wisconsin, this 25th day of January 1926.

EDWARD C. DAMROW.
